UNITED STATES PATENT OFFICE

JULIUS C. SPECK, OF CLEVELAND, OHIO

DESIGN FOR A CIGARETTE LIGHTER

Application filed July 10, 1931. Serial No. 40,481. Term of patent 14 years.

To all whom it may concern:

Be it known that I, JULIUS C. SPECK, a citizen of the United States of America, residing at Cleveland, in the county of Cuyahoga and State of Ohio, have invented a new, original, and ornamental Design for a Cigarette Lighter, of which the following is a specification, reference being had to the accompanying drawing, forming a part thereof.

The figure is a perspective view showing my new design.

I claim:—

The ornamental design for a cigarette lighter as shown.

JULIUS C. SPECK.
